UNITED STATES PATENT OFFICE.

CHARLES H. BROWN AND CHARLES C. PARKER, OF EUREKA, UTAH.

ORE-SEPARATOR.

1,152,351.

Specification of Letters Patent. Patented Aug. 31, 1915.

Application filed April 20, 1915. Serial No. 22,634.

To all whom it may concern:

Be it known that we, CHARLES H. BROWN and CHARLES C. PARKER, citizens of the United States, residing at Eureka, in the 5 county of Juab, State of Utah, have invented certain new and useful Improvements in Ore-Separators; and we do hereby declare the following to be a full, clear, and exact description of the invention, such as 10 will enable others skilled in the art to which it appertains to make and use the same.

This invention relates to ore separators.

The object of the invention resides in the provision of a device of the character named 15 embodying an improved construction whereby the fine gold present in river and beach sands may be efficiently separated from the sand and recovered.

With the above and other objects in view 20 the invention consists in the details of construction and in the arrangement and combination of parts to be hereinafter more fully described and particularly pointed out in the appended claim.

25 In describing the invention in detail reference will be had to the accompanying drawings wherein like characters of reference denote corresponding parts in the several views, and in which,

30 Figure 1 is a view in elevation of an ore separator constructed in accordance with the invention; and Fig. 2, a view similar to Fig. 1 with certain of the parts in section.

Referring to the drawing the invention is 35 shown as comprising a casing A having a conical lower end 10 and a reduced upper end 11. The outer end of the portion 10 of the casing terminates in an outlet mouth 12. Leading from the reduced upper end 11 of 40 the casing A is an air inlet pipe 13, while a material inlet pipe 14 enters the top of the reduced upper end 11 and terminates in a depending portion 15 disposed within the casing A and extending longitudinally of 45 the latter. Rotatably mounted in the top of the reduced upper end 11 of the casing and extending through the portion 15 of the material inlet pipe 14 is a shaft 16 which has fixed on its lower end within the casing 50 a conical spreader 17. This shaft 16 is adapted to be rotated through the medium

of connection with any suitable source of power. Disposed within the casing A beneath the spreader 17 is a conical casing 18 having an opening 19 in its upper end and 55 an opening 20 in its lower end. Extending laterally from the casing 18 and passing through the wall of the casing A is a pipe 21 which communicates with the interior of a casing 22 which latter has mounted there- 60 in a suction fan 23 adapted to be rotated through the medium of connection with any suitable source of power. It will thus be obvious that the interior of the casing 18 is connected directly with the interior of the 65 casing 22 through the medium of the pipe 21. The casing 22 is in turn connected by a pipe 25 with a dust collector 26.

In operation of the device the fan 23 and the spreader 17 are simultaneously rotated. 70 Material supplied by the pipe 14 will fall upon the top of the spreader 17 and by force of the air current entering through the pipe 13 the sand or ore is not only agitated and dried, but the separation of the heavier par- 75 ticles from the lighter particles, the lighter particles of gold or other metals being sepa- rated at the bottom of the spreader 17 and there being taken into the interior of the casing 18 through the opening 19, such par- 80 ticles then being forced by the action of the fan 23 through the pipes 21 and 25 into the dust collector 26 at which latter point the product is held until removed.

The coarser material or waste after be- 85 ing separated from the metal, as previously described, drops into the lower portion 10 of the casing A and is discharged through the outlet 12. It will also be noted that owing to the presence of the opening 20 in the 90 lower end of the casing 18 a blast of air will pass inwardly through the outlet 12 and will serve to draw up and save any fine dust or material that might possibly pass downward in the casing A beyond the upper end of the 95 casing 18.

What is claimed is:—

A device of the class described comprising a casing having an air inlet and a material inlet in its upper end and a material 100 outlet in its lower end, a rotatable spreader within the casing beneath the material inlet,

a second casing disposed within the first casing beneath the spreader and having openings in its upper and lower ends respectively, said lower end being in proximity to the lower end portion of the outer casing; and a suction device connected with the interior of the second casing.

In testimony whereof, we affix our signatures, in the presence of two witnesses.

CHARLES H. BROWN.
CHARLES C. PARKER.
